UNITED STATES PATENT OFFICE

AUGUSTINUS EDWARD JONSSON, OF LIDINGO, SWEDEN

DRYING APPARATUS

Application filed February 14, 1929, Serial No. 339,999, and in Sweden February 14, 1928.

This invention relates to drying apparatus of the kind comprising a rotating or oscillating cylinder containing hollow heating bodies or units heated by means of steam, hot water, or any other suitable heating fluid, and which are adapted to support and distribute the goods to be dried.

The invention is essentially characterized by the feature that the hollow heating bodies or units consist of fixed plane shelves extending through the whole length of the cylinder and grouped in parallel on opposite sides of a space extending in a diametrical plane perpendicular to the plane of the shelves and communicating with the feeding and discharge opening in the wall of the cylinder. This arrangement of the heaters serves the purpose of producing a stirring or mixing of the goods being dried in such a manner that during the rotating movement of the cylinder, which is necessary for the stirring operation, the goods will slide from one heater to another, so that any violent tumbling motion such as would be detrimental to delicate or brittle material is avoided.

The heaters, which are hollow and are supplied with a suitable heating fluid, for instance hot water, steam or the like, may be connected in any suitable manner, for instance in a single series, or partly in series and partly in parallel.

In order to increase the capacity of the drying apparatus, the cylindrical part, and in some cases also the ends of the cylinder, may be double walled thereby to provide heating jackets which essentially increase the heating surface. The jackets may directly communicate by means of pipes with the heaters, in order to allow the heating fluid to pass freely during the drying operation.

The invention will be more particularly set forth in the following description in connection with the embodiment illustrated in the accompanying drawings, in which

Fig. 1 is a side elevation of the drying apparatus as a whole;

Fig. 2 is a cross-section thereof, taken approximately on the line II-II of Fig. 1;

Fig. 3 is a fragmentary plan view of one of the heating bodies on an enlarged scale,

the supporting column being shown in section; and

Fig. 4 is a fragmentary sectional view taken approximately on the line IV-IV of Fig. 3.

Referring to the drawings, 1 designates the drying cylinder, which is supported by rollers 2 and is adapted to be given a rotating or an oscillating movement by means of a motor driven gearing 3. The hollow heating bodies 4 are supplied with steam, hot water or any other suitable heating fluid, and are arranged on opposite sides of a plane diametrically across the cylinder through the axis thereof and preferably perpendicularly to said plane. The side and end walls of the cylinder may be of double wall construction thereby to provide a heating jacket 5 communicating with the heating units by means of pipes. The heating units 4 and the interior wall of the cylinder are provided with ribs 6. The heating fluid is conveyed to the heating units by means of the pipe 7 and, after passing through the several units of the drying cylinder, is carried off by the pipe 8. Feeding and discharging openings 9 are provided for the material being dried.

In order to facilitate a rapid and efficient drying operation, the interior of the cylinder may be subjected to a vacuum, and to this end a pipe 11 is shown in the drawing, which pipe may be connected with a vacuum pump, not shown, through the condenser 10 and the pipe 12. The heating units 4 are supported at one end on flanges 16 carried by supports 15 or columns 15 disposed within the cylinder and at the opposite end are secured in notches formed in the ribs 6 on the inner wall of the cylindrical heating casing.

The connection of the inlet and outlet pipes to the heaters 4 and jackets 5 may be effected in any convenient manner. The units are interconnected in series by means of pipes extending across the diametrical space between the two groups of units as shown in Fig. 2.

It is believed that the operation of the apparatus will be obvious from the foregoing. After the material to be dried has been charged into the cylinder, steam, hot water or other fluid is supplied to the heating units

and the motor started thereby to rotate the cylinder. This rotation will necessarily cause the material to move about within the cylinder, but because of the wide shelves formed by the heating units the material will be protected against any violent falls or jars.

Having thus described my invention what I claim is:—

1. A drying apparatus, comprising a rotatable cylinder, hollow heating units disposed within said cylinder for the reception of a heating fluid, said units forming flat shelves extending through the whole length of the cylinder and grouped in parallel at opposite sides of a free space extending diametrically through the axis of the cylinder perpendicular to the plane of the shelves, each of said shelves extending from the circumference of the cylinder to the said diametrical free space, said space communicating with feeding and discharging openings in the wall of the cylinder.

2. A drying apparatus, comprising a rotatable cylinder, a plurality of supporting columns fixed in said cylinder and extending diametrically thereof, a plurality of hollow heating units each supported at one end on said column and at its opposite end on the wall of the cylinder, said units forming shelves extending through the whole length of the cylinder and grouped in parallel at opposite sides of a plane extending diametrically through the axis of the cylinder perpendicular to the plane of the shelves and communicating with feeding and discharging openings in the wall of the cylinder.

AUGUSTINUS EDVARD JONSSON.
